Attorney

UNITED STATES PATENT OFFICE.

WILLIAM H. MAROLF, OF IRON RIVER, MICHIGAN.

LUNCH-CABINET FOR AUTOMOBILES.

1,334,107.

Specification of Letters Patent. Patented Mar. 16, 1920.

Application filed September 8, 1917. Serial No. 190,361.

To all whom it may concern:

Be it known that I, WILLIAM H. MAROLF, a citizen of the United States, and resident of Iron River, in the county of Iron and State of Michigan, have invented certain new and useful Improvements in Lunch-Cabinets for Automobiles, of which the following is a specification.

This invention relates to new and useful improvements in portable lunch cabinets, and the primary object of the invention is to provide a portable lunch cabinet designed to be carried upon a motor vehicle and equipped with an improved and conveniently removable ice chamber supported in spaced relation to the main walls of the cabinet so as to effectively cool the contents of the latter.

A further object of the invention is to provide a device of this character which is easily and simply constructed, inexpensive to manufacture, and one which will be very efficient in operation.

With these and numerous other objects in view, my invention consists of the novel features of construction, combination and arrangements of parts which will be herein referred to and more particularly pointed out in the specification and claim.

In the accompanying drawings;

Figure 1 is a front elevation of the cabinet;

Fig. 2 is an end elevation of the same, showing the cabinet partly covered with some heat resisting material;

Fig. 3 is a front elevation of the cabinet showing the door open;

Fig. 4 is a perspective view of one of the shelves; and

Fig. 5 is a detail vertical section through the front of the cabinet with the door closed.

Fig. 6 is a detail vertical section through the lower part of the cabinet.

In describing my invention I shall refer to the drawings in which similar reference characters designate corresponding parts throughout the several views.

The cabinet, is formed of a substantially rectangular shaped casing, constructed entirely of galvanized iron, or any other appropriate material and being provided with an open front 1, and sides 2. The open front 1 of the casing, is provided with a door 4, hinged to one side or the other as shown at 5, said door being adapted to fit into a countersunk portion 6 in the front

wall 1 of the casing, and having a bar 7 extending around the marginal edges thereof and positioned in said countersunk portion. A felt strip 8 is arranged about the marginal portion of the opening in the front of the casing, over which the door is positioned to make the door perfectly air tight, when in closed position. The door is provided with a lock 9 if desired. The back wall of the casing, is provided with a transversely extending felt or rubber strip 10 along its upper edge, that engages the automobile when the cabinet is in position, and will prevent the automobile from being marred.

The casing is provided with a plurality of horizontally disposed shelves 11, which are spaced therein, said shelves being supported by angle bars 12 secured to the inner faces of the opposite sides 2 of the casing. The bottoms of certain of the shelves 11 are provided with transversely extending spaced brackets 13 intermediate the ends thereof,

which receive the upper portions of the vertical partition members 14, the lower portions of which rest upon the upper surfaces of the shelves disposed directly there beneath. These partitions may be positioned anywhere along the shelves according to where the holding brackets 13 are secured.

The top partition is secured to the bottom surface of the top of the casing, and the lower partition extends downwardly and rests upon the bottom of said casing. Each

of the shelves 11 is provided along its front edge with an upwardly projecting flange 15, that will prevent articles positioned thereon from slipping out when the door is opened, and if desired, the shelves may be perforated as shown at 16, to permit cool air to circulate through the cabinet when ice is placed therein and the device used as a refrigerator. In Fig. 3 I have shown a partition at the bottom placed to one side,

so as to form an ice receiving chamber in the bottom of said cabinet, but if desired, the ice may be placed at any point therein. It is obvious, that when positioned at the top a draining tube or the like is used to carry the water to the bottom of the cabinet.

A faucet 17 is secured to the front wall of the casing adjacent the bottom thereof so as to drain the water given from the melting ice.

In Figs. 3 and 6 of the drawings I have shown a cabinet provided with a supple-

mental ice receiving chamber 23, that is provided with an opening in the front face normally closed by a door 24, and said ice receiving chamber having a perforated bottom 25, through which the water that melts from the ice drains into the bottom of the cabinet. The ice receiving chamber 25 is provided at its corners with outwardly extending ribs 26, that fit into angle iron supporting braces 27 secured within the cabinet to support the ice chamber in position. The ice receiving chamber is easily removable, when it is desired to replenish the ice. The partition adjacent the ice receiving chamber is perforated adjacent its upper portion as shown at 27, so as to allow the cool air to pass through into the chamber formed by said partition and the outer side wall of the cabinet. The object of spacing the walls of the ice receiving chamber from the walls of the cabinet, is to prevent direct contact of the walls of the chamber with the walls of the cabinet so to help in preserving the ice.

25 The casing is formed, to fit on an automobile, preferably on the running board thereof, and to secure the cabinet in position, a downwardly extending hook 18, is secured to the front wall of the casing, adjacent the bottom thereof and extends below said bottom, the hook being adapted to engage under the outer edge of the running board. If desired, a number of hooks may be employed. The top portion of the casing has secured thereto an upwardly extending bracket 19, the same being connected with one end of the coil spring 20, which has a snap fastening 21 on the opposite end, and adapted to engage a ring or the like on the automobile to securely hold the cabinet in position and prevent the same from rattling during operation of the automobile. Although the cabinet is preferably secured to the running board of an automobile, it is obvious that it may be secured to various

other places thereon. In Fig. 2 of the drawings I have shown the cabinet partially covered with some form of heat resisting material 22, preferably asbestos, to keep the heat from the interior of the cabinet. The use of this heat resisting material is optional, and any desired type may be employed.

This type of portable lunch cabinet is especially useful for tourists or the like, as food may be transported in the same with very little trouble and inconvenience to the tourists. The cabinet forms a very practical refrigerator and will keep the food cool during transportation. The means for securing the cabinet to the automobile is very simple and the same may be employed for attaching the cabinet to various makes of cars.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having fully described my invention what I claim as new and desire to secure by Letters Patent is:

In combination, an outer casing, angle iron guides arranged in the casing, a supplemental ice receiving chamber, and spacing ribs projecting from the corners of the supplemental chamber slidably mounted in the guides and maintaining the supplemental chamber in spaced relation to the walls of the casing.

In testimony whereof I affix my signature hereto.

WILLIAM H. MAROLF.
